VERTICAL INCINERATOR GRATE

Clarke H. Brooke, Seattle, Wash.

Application September 21, 1954, Serial No. 457,362

2 Claims. (Cl. 126—163)

My invention relates to grate construction; and, more particularly, to a cast iron vertical incinerator grate. Provision is made to prevent accumulation of ashes on the face of the grate by having precipitous walls and the grate is formed to facilitate molding of the same and to simplify its installation in various types of incinerators.

A vertical grate has advantages over the conventional horizontal grate, particularly in incinerators where considerable ashes are allowed to accumulate in the bottom of the incinerator between cleanings, and the furnace is frequently overloaded. One difficulty with horizontal grates is deterioration from having live coals lying on the surface. On the other hand, the horizontal grate is less efficient if a layer of ashes and soot is left on the grate. For these reasons, there has been a more or less recent development in the use of vertical grates in incinerators and the grate disclosed in this application has several advantages over those previously found on the market. Prior grates with sloping faces have had the characteristic of forming a surface for the collection of material, particularly ashes, which reduced the efficiency of the air openings or entirely closed them. Among other disadvantages, these grates have had irregular shapes in rear elevation so as to make it difficult for a mason to brick around the grate and some have had difficult structures to mold.

The objectives of my invention include, therefore: to devise a vertical grate constructed so as to reduce to a minimum the obstruction of the air openings with ashes and other debris, to devise a vertical grate facilitating molding and installation of the same, to provide a grate adaptable to various types and sizes of incinerators and to improve the construction of the air passageways in such grates.

The invention will be best understood, together with additional objectives and advantages over previous constructions, from a reading of the following description, when read with reference to the drawings, in which:

Figure 1 is a front elevational view of a specific embodiment of my incinerator grate;

Figure 2 is a sectional view taken on line 2—2 of Figure 1;

Figure 3 is a sectional view taken on line 3—3 of Figure 1;

Figure 4 is a perspective view of one type of an incinerator;

Figure 5 is a fragmentary view, partly in section, taken on line 5—5 of Figure 4;

Figure 6 is an enlarged sectional view taken on line 6—6 of Figure 5;

Figure 7 is a horizontal sectional view showing the mounting of the incinerator grate in a steel drum;

Figure 8 is an elevational, sectional view showing the mounting of superposed grates; and

Figure 9 is a fragmentary sectional view showing in enlarged detail the area of joinder of upper and lower grates.

2

The incinerator grate 10 may be installed in various types of incinerators, one formed of brick construction being shown in Figure 4, and the use of a steel drum being suggested in Figure 7. The incinerator may be 5 of various sizes including large incinerators for public buildings, manufacturing concerns, grocery stores, and the like, and also including small incinerators for households. In the smaller incinerators, i. e., for household use, a single grate may be used of small size, as for 10 example, an 18 inch high 4 inch I. D., 16 pound grate operative with a maximum incinerator capacity of approximately 12.4 cubic feet. A large size would be 18 inches high, 7½ inch I. D. grate, weighing approximately 38 pounds and operative singly with approximately 15 48 cubic feet of capacity. In large incinerators, it may be desirable to use more than one grate, as suggested in Figure 5, or to use superposed grates as shown in Figure 8.

Referring to Figure 1, the grate 10 is preferably molded 20 as a one piece unit from cast iron as experience has shown that this material has the longest life, against rusting and deformation from heat, of materials of economical manufacture. No machine work is required after casting. The back 12 is completely open and the inner 25 walls 14 diverge from the forward side to rear side 12 so that the mold may be readily removed. It will be understood that this leads to economical manufacture of the unit because in more closed bodies it is necessary to use a core which is expensive to make and difficult to 30 remove. Core making is one of the most costly operations in a foundry.

Referring to Figure 1, side walls 20, 22 are substantially parallel and the bottom edge 24 lies in a plane normal to the side walls. Likewise top wall 26 lies in a 35 plane normal to side walls 20, 22 except for the relieved top corners 28. This means that substantially a rectangular outline is presented for bricking-around the same, as will be understood from Figure 5, so that the inner fire brick lining 30 may be laid around the grate with facility. 40 The outer layer of brick 32 shown in Figure 5 may be ordinary brick, or, in some installations, fire brick. The walls rest on a concrete foundation.

Another representative type of installation is shown in Figure 7 wherein a cylindrical incinerator is formed either 45 by reinforced concrete, or, as in Figure 7, by the steel drum 36. Again, the fire brick lining 38 can be laid around the grate with a minimum of time because of its rectangular outline in front elevation. The grate may be fastened in place in this application by a pair of J-bolts 50 having their hooks engaged in one of the front openings of the grate and having washers and nuts 42 abutting the outer surface of drum 36. The rear edge 12 of the grate lying in a plane normal to parallel side walls 20, 22, grate 10 will fit snugly against a cylindrical surface such as drum 36. This is because the rear edges of side walls 20, 22 lie on lines of generation of the cylinder. 55 Almost no other shape of grate will conform to the inner wall of the drum and it is advantageous to have this easy and snug fitting to the cylindrical incinerators which are so often used.

The front wall 50 of grate 10 has a series of superposed openings 52 extending from a location spaced from bottom edge 24 to adjacent top wall 26. When considerable consumed material has piled on the floor of the incinerator some of the lower openings may be blocked, 60 and in order to provide some openings that will always be free and also to provide a source of air to gases as they ascend from burning material, it is desirable to have a number of these openings. Eight openings 52 have been shown in the grate illustrated in the drawings and six may 65 be taken as a minimum number for efficient operation of the grate in incinerators. As indicated in Figure 8, it 70

may be desirable in some installations to increase the number of openings beyond eight. The vertical height of openings 52 is increased from bottom to top of the series. This is desirable for several reasons. First it means that if lower openings are covered because of the level of ashes in the incinerator, the effective total area of openings 52 will be reduced less than if the openings were of equal size. Furthermore, the lower openings nearest to the source of air, such as ducts 54, 56 in Figures 5 and 7 respectively, will be less likely to starve the openings 52 above. Air enters ducts 54, 56 because of the negative pressure created by combustion in the incinerator chamber 58; and the entering air stream will have considerable velocity and pressure, at least at the lower openings. Ducts 54, 56 should be greater in area than the total area of openings 52 appearing on the face of grate 10. As shown in Figure 5, the uppermost edge of the duct should be slightly below the upper edge of the solid lower portion of the front wall 50 so that the duct does not feed directly to the lower openings.

Front wall 50 forms webs 60 between openings 52 and webs 60 extend inwardly forming flanges 62 which terminate in centrally rearwardly opened recesses 64. Recesses 64 have contours similar in plan to the contour of the walls of grate 10. The recesses decrease in size from bottom to top of the series of webs 60. This, in effect, decreases the area of the vertical air passageway in grate 10 having a funneling action maintaining a high pressure of the air from bottom to top, even though air escapes through each opening 52. Flanges 62 lap side walls 20, 22 and have integral connection therewith. Webs 60 are relieved at their upper forward and lower rearward edges as shown in Figure 2.

The outer edges of webs 60 are superposed forming a vertically aligned bank providing no recess or inclined surface outside of openings 52 on which ashes would have any tendency to rest. A less precipitous front face would tend to collect ashes and would form a surface on which debris could build, whereby the openings 52 could be partially covered, reducing the efficiency of the grate. The vertical front wall 50 thereby adds to the efficiency of the grate so that there will be a minimum tendency to cover the openings. As in many installations the incinerator is not tended like a furnace by frequently removing ashes or by carefully loading the same to prevent the fuel from covering the grate, it is quite important to take every measure to prevent blocking of openings 52.

In large incinerators it may be desirable to use two or more grates as shown in Figure 5 and in incinerators of large capacity and considerable height, grates may be superposed as shown in Figure 8. For economical manufacture, without having to make completely new molds for taller grates, the construction of Figure 8 has been devised, working with the usual pattern for one of the grate sizes. The mold is changed on the lower grate 70 by blanking off the two lower openings 52 which would normally appear and providing an opening 72 in top wall 26. Upper grate 74 is formed by reproducing grate 10 from a location immediately below lowermost opening 52 to the top of the grate. As shown in Figure 9, the abutting portions of the grates have a plurality of bead welds 76 securing them together.

This grate has proved to be very efficient in operation, economical of manufacture and installation, and adapt-

able to various types of incinerator installations. The usual incinerator owner wants an incinerator that will operate with infrequent cleaning of ashes and which will operate although loaded to the top with debris, and incinerators with the present grate have met these demands. I do not wish to be limited to the exact details of construction shown in the drawings, but wish to cover those modifications within the scope of the invention which may occur to those skilled in the art, as defined by the appended claims.

I claim:

1. A vertical grate for incinerators, comprising: a hollow cast iron body molded as one piece, the front wall of said body being substantially hemi-cylindrical and merging into substantially parallel flat vertical side walls, the body having an open bottom and an open back and the edges of the body at the bottom and back lying in planes normal to said side walls and to each other, the body having a top wall lying in a plane normal to said side walls, the inner surfaces of the side walls flaring to the back edges to facilitate removal of the mold, approximately the lower third of said front wall being solid and of uniform thickness and said body having a series of at least six superposed openings spaced apart up and down the remainder of said front wall, said openings being unobstructed and being horizontally elongated to extend substantially from one side wall to the other side wall, said openings being vertically broader and of increasing effective area from bottom to top of the series, the portions of the front wall separating the openings being in the form of integral webs inwardly extending beyond the interior surface of the lower one-third of the front wall forming flanges instanding into said hollow body, the inner margins of said flanges forming coaxial rearwardly open recesses having substantially semi-circular contours, the recesses decreasing in horizontal area from bottom to top of the series of recesses.

2. A vertical grate for incinerators, comprising: a hollow cast iron body molded as one piece, the front wall of said body being substantially hemi-cylindrical and merging into substantially parallel flat vertical side walls, the body having an open bottom and an open back and the edges of the body at the bottom and back lying in planes normal to said side walls and to each other, the body having a top wall lying in a plane normal to said side walls, approximately the lower third of said front wall being solid and of uniform thickness and said body having a series of at least six superposed openings spaced apart up and down the remainder of said front wall, said openings being unobstructed and being horizontally elongated to extend substantially from one side wall to the other side wall, the portions of the front wall separating the openings being in the form of integral webs, said openings being vertically broader and of increasing effective area from bottom to top of the series.
